UNITED STATES PATENT OFFICE.

FRANKLIN S. SPRINGSTEAD, OF ROCHESTER, NEW YORK.

AUTO SIGNAL.

Application filed May 31, 1923. Serial No. 642,519.

To all whom it may concern:

Be it known that I, FRANKLIN S. SPRINGSTEAD, a citizen of the United States, residing at Rochester, in the county of Monroe 5 and State of New York, have invented certain new and useful Improvements in Auto Signals, of which the following is a specification.

The object of this invention is to provide 10 a new and improved direction and stop signal in combination with a spot light.

This and other objects of this invention will be fully illustrated in the drawings, described in the specification and pointed 15 out in the claims at the end thereof.

In the accompanying drawings:

Figure 1 is a top plan view of a portion of the front of an automobile with the direction and stop signal mounted thereon.

Figure 2 is a rear elevation of the same portion of the automobile illustrated in top plan view in Figure 1 with the direction and stop signal mounted thereon.

Figure 3 is a horizontal sectional view of 20 the signal the section being taken on the line 3^x—3^x of Figure 2.

Figure 4 is a vertical sectional view of the signal, the section being taken on the line 4^x—4^x of Figure 1.

Figure 5 is a vertical sectional view of 25 the signal, the section being taken on the line 5^x—5^x of Figure 1.

Figure 6 is a detail sectional view of the operating levers of the signal and supports 30 therefor.

In the several figures of the drawing like reference numerals indicate like parts.

In the signal forming the subject matter 35 of my present invention, a swinging indicator 1 is mounted on top of a rocking sleeve 2 that is carried by a hollow supporting bracket 3. The supporting bracket 3 is clamped to the standard 4 of the windshield by means of the clamp 5 and forms a rocking bearing for the end of the hollow bracket to turn therein. A pair of collars 40 6 and 7, one located on top of the clamp 5 and the other located at the bottom of the clamp 5 are provided on the hollow bracket 3 and form thrust bearings therefor.

The upper edge of the clamp is cut away 45 for a distance to receive the pin 8 projecting from the hollow bracket 3. Surrounding the bracket 3 above the clamp 5 is the torsion spring 9 having the lower end there-

of anchored to the clamp 5 and the upper end thereof anchored to the hollow bracket 3. The action of this spring is to swing the hollow bracket forwardly until the pin 8 60 engages the end of the cut away portion of the clamp 5. The stop formed in this way arrests a further swinging motion of the bracket 3 toward the front and holds this bracket in an angularly projecting position from the body of the car as illustrated in Figures 1 and 2. When the indicator or its supporting bracket is hit by an object from the front the bracket can swing back against the torsion of the spring 70 9 and thus allow the object to pass by without doing any damage to the signal. The torsion spring will quickly swing the bracket 3 and its indicator back to its normal position after the object or obstruction that had 75 come in contact with it has passed by.

As pointed out above, the indicator 1 is mounted on a rotating sleeve 2. This sleeve has a slot 10 cut into it near the inner end thereof into which a pin 11 carried by the 80 bracket 3 is adapted to project. The engagement of this pin with the sleeve holds the sleeve in place on the bracket but permits a turning motion thereof. In addition to the circular slot 10 the sleeve is also 85 provided with a spiral slot 12. A horizontally sliding pin 13 projects into this spiral slot at each side of the bracket 3 and turns the sleeve 2 when the pin 13 is operated to slide back and forth in the bracket 3 90 as will presently be described.

The bracket 3 is slotted at two diametrically opposite points 14 and 15 to form guides for the rollers 16 and 17 carried by the pin 13 to roll therein. These same rollers also engage the spiral slot 12 of the sleeve 2 so that on the movement of the pin 13 within the bracket 3 the sleeve may be turned in either one or the other direction. The pin is moved back and forth by means 100 of the flexible cable 18 carried in the flexible guide sleeve 19. The outer end of this cable is suitably fastened to the pin 13 while the other end is attached to the end of the operating handle 20. This is done by extending the flexible cable and its guide sleeve through the hollow bracket 3, the flexible hose 21 fastened to the end of the hollow bracket and the tube 22 fastened to the steering column 23 and connected to the end of 110 the hollow bracket 3 by means of the flexible hose 21. The upper portion of the tube 22

projects angularly to one side of the steering column 23 and its upper end is located just below the rim of the steering wheel 24. In the end of the tube 22 are mounted to 5 slide the operating handles 20 and 26. To the end of the handle 20 is suitably fastened the end of the flexible cable 18. The handles 20 and 26 are adapted to be pushed in and pulled out of the end of the tube 22 in 10 order to pull or push the cable that is attached thereto to operate the signal in the desired manner. Thus in pushing in on the handle 20 the cable 18 is pushed by it so that the pin 13 with its rollers 16 and 17 is 15 forced outwardly in the slots of the bracket 3 which in turn causes the sleeve 2 to rotate in one direction while a pulling on the handle 20 will cause the sleeve 2 to rotate in the opposite direction. For the purpose of holding 20 the sleeve in a predetermined position the stem of the handle 20 is notched on one side thereof and a spring latch 25 mounted on the inside of the tube 22 is adapted to engage into these notches as the handle is 25 operated, and temporarily hold the handle in the desired position. In rotating, the sleeve 2 is held against endwise movement by the pin 11 which engages into the slot 10 and guides the sleeve during its rotating 30 motion in either one or the other direction.

The indicator 1 comprises a tubing having a reflector 28 with a lens 29 in front of it mounted in one end thereof. The other end of the tube is closed by a suitable cover 35 30 that is held in place by the spring latches 31. The sides of the tube as well as the top thereof have the arrows 32 cut into it and the openings formed by these arrows are closed by a cylindrical sheet of a colored celluloid 33 or similar material that fits 40 snugly against the inner wall of the tube forming the indicator.

In the focal center of the reflector 28 is mounted the electric light bulb 34 and in 45 the middle of the inside of the indicator is mounted another electric light bulb 35. The light 35, its reflector 28, and lens 29 form a spot light in the end of the indicator that can be directed into any direction by swinging 50 the indicator as will presently be described. The light 35 mounted on the inside of the indicator in the middle thereof serves to illuminate the arrows cut into the sides and top of the tube forming the indicator. 55 The celluloid windows formed by the sheet of celluloid on the inside of the indicator are preferably of a color that quickly attracts the attention of anyone in front or in rear of the car so that the operation of the signal or indicator is readily observed by those interested in the movement of the car.

The indicator is pivoted in the middle of 60 the top of the sleeve 2 near the outer end thereof and for this purpose a hollow stud

36 is fastened to the indicator tube. This stud is mounted to rotate in the sleeve 2 being provided with a collar at the top and bottom of the tube 2 that hold the stud in place on the tube and permit its rotation 70 therein. The stud 36 is rotated by means of another flexible cable 37. This cable projects past the hollow stud 36 being guided by two holes provided in the partitions 38 and 39 located one on each side of the stud 36. Wound around the stud 36 is a short 75 flexible friction cable or other flexible friction member 40 having one end thereof fastened to the flexible cable 37 on one side of the stud 36 while the other end of the friction cable 40 is fastened to the flexible cable 37 at the other side of the stud 36. The friction cable is fastened to the stud in the middle thereof so that on the reciprocation 80 of the flexible cable 37 the short flexible friction cable is wound up on one side of the stud and unwound on the other side thereof causing a rotation of the stud 36 due to the firm grip the flexible friction cable has on the stud 36 when being simultaneously 85 wound up thereon from one side thereof and unwound from the opposite side thereof.

The handle 26 to which the cable 37 is attached for the operation of the indicator is mounted parallel to and is the same in construction as the handle 20 above described in connection with the turning of the sleeve 2. In operating the handle 26 by sliding it in or out of the tube 22 the indicator 1 can, therefore, be swung to the right or left of the straight forward position illustrated in Figure 1 and thus indicate to anyone in front or rear of the car the direction in which the car is about to turn. To indicate that the car is about to stop the indicator 1 is swung vertically from the horizontal position to a vertical position as indicated in dotted lines in Figure 2. This is done by turning the sleeve which carries the indicator 1 by means of the handle 20. For the 90 purpose of directing the spot light in any direction the indicator can be swung if necessary through an arc of 360° by simply operating the handle 26 to turn the stud 36 as above described until the indicator points 95 in the desired direction.

I claim:

1. In an automobile signal, the combination of a hollow angle bracket mounted to swing and project horizontally to one side of the vehicle, means for yieldingly holding said bracket in a predetermined angularly projecting position on the vehicle, a rotating sleeve carried on the outer horizontal end of said bracket, a swinging indicator mounted on said rotating sleeve, means for rotating said sleeve and swinging said indicator in a vertical plane and means for swinging said indicator on said rotating sleeve in a horizontal plane to place said 100

indicator into any angular horizontal position or a vertical position.

2. In an automobile signal, the combination of a hollow angle bracket mounted to swing and project horizontally to one side of the vehicle, means for yieldingly holding said bracket in a predetermined angularly projecting position on the vehicle, a rotating sleeve carried on the outer horizontal end of said bracket, a swinging indicator mounted on said rotating sleeve, means for rotating said sleeve and swinging said indicator in a vertical plane and means for swinging said indicator on said

10 rotating sleeve in a horizontal plane to place said indicator into any angular horizontal position or a vertical position, a search light mounted in the front end of said indicator.

3. In an automobile signal, the combination of a bracket, a sleeve mounted on said horizontal bracket, an indicator mounted to swing in a horizontal plane on said sleeve, said sleeve having a spiral guide slot provided therein, a pin projecting from said 25 bracket and engaging said spiral slot in said sleeve and means adapted to reciprocate said pin in said bracket to cause said pin to turn said sleeve by reason of its engagement with said spiral slot.

4. In an automobile signal, the combination of a bracket, a sleeve mounted to rotate on said bracket, a pivot stud carried in the end of said sleeve, a sliding cable mounted to slide past said pivot stud, a friction cable wound around said stud and fastened with its ends to said sliding cable at each side of said stud, and means for sliding said cable and cause said friction cable to rotate said pivot stud, an indicator mounted on said pivot stud.

5. In an automobile signal, the combination of a hollow bracket, a sleeve mounted to rotate on one end of said bracket, a sliding pin mounted in said hollow bracket, said sleeve having a spiral slot cut into it, said sliding pin being adapted to engage said spiral slot and rotate said sleeve on the

reciprocation thereof within said bracket, a pivot stud mounted to rotate in said sleeve, a friction cable wound around said stud 50 and means to wind up and unwind said friction cable from said pivot stud to rotate said friction stud, an indicator carried by said pivot stud, and means for reciprocating said pin within said bracket. 55

6. In an automobile signal, the combination of a hollow bracket, a sleeve having a spiral slot cut into it mounted to rotate on said bracket, a pin mounted to reciprocate within said bracket and engaging said 60 spiral slot to rotate said sleeve on the reciprocation of said pin within said bracket, a pivot stud carried by said sleeve, an indicator carried by said stud, a friction cable engaging said stud, a flexible sliding cable 65 operating said friction cable to wind up and unwind said friction cable from said stud and cause said stud with its indicator to rotate, a second sliding cable for reciprocating said pin, a handle for both of 70 said sliding cables at the outer ends thereof, and means for guiding said sliding cable from the bracket to said handles.

7. In an automobile signal the combination of a hollow bracket, a socket adapted 75 to be mounted to the body of an automobile and forming a bearing for said bracket to swing therein, spring pressed means for yieldingly holding said bracket in a predetermined position in said socket, a sleeve 80 mounted to rotate on the outer end of said bracket, means for rotating said sleeve, a pivot pin mounted to rotate in the outer end of said sleeve as well as rotated with said sleeve, an indicator mounted on the upper 85 end of said pivot pin outside of said sleeve, said indicator being adapted to be swung in a horizontal plane by rotating said pivot pin and being adapted to be swung in a vertical plane by rotating said sleeve with 90 said pivot pin.

In testimony whereof I affix my signature.

FRANKLIN S. SPRINGSTEAD.
